UNITED STATES PATENT OFFICE.

JOHN H. MILLS, OF BOSTON, MASSACHUSETTS.

SECTIONAL BOILER.

SPECIFICATION forming part of Letters Patent No. 449,379, dated March 31, 1891.

Application filed November 15, 1890. Serial No. 371,609. (No model.)

To all whom it may concern:

Be it known that I, JOHN H. MILLS, a citizen of the United States, residing at Boston, in the county of Suffolk and State of Massachusetts, have invented new and useful Improvements in Sectional Boilers, of which the following is a specification.

This invention relates to sectional boilers, the object being to provide for steam and especially for hot-water-heating apparatus and analogous uses an improved boiler consisting of cast-iron hollow sections of peculiar construction and arrangement composing the individual units of such boiler, whereby increased heating-surface is obtained without increasing the cost of manufacture, all as hereinafter fully set forth.

In the drawings forming part of this specification, Figure 1 is a front elevation, partly in section, of a boiler embodying my improvements. Fig. 2 is a side elevation, partly in section. Fig. 3 is a sectional view about on line 3 3 of this figure. Fig. 4 is a rearview of a section located at the rear end of the grate-bars, as below described. Fig. 5 is a perspective view of one of the main sections of the boiler, the outflow and return drums with which all of the sections of the boiler communicate, and a pipe connection between said drums, the purpose of which is fully described below.

One essential object of this invention is to secure increased efficiency and power to absorb heat for a liquid circulation by placing a part of the heating-surface below the grate-line, which surface will be acted upon by the radiant heat of the coals on the grate and the high temperature of the ash-pit, but which heat is entirely lost in boilers having no heat-absorbing surface below said grate-line. While some wrought-iron or shell boilers have an extension of their water-spaces below the grate-line and to the floor, they do not and cannot also extend their smoke-flues to render available the surface so obtained.

Heretofore in the construction of cast-metal boilers composed of separate sections they have been formed of certain tubes and flues designed to stand upon foundation-walls of brick or iron, such walls forming the ash-pit of the completed boiler.

While the sectional boiler just referred to

has many desirable features of construction and operation as a steam-generator, they do not cover certain modern demands in the way of a heating apparatus not intended to generate steam as the heating agent, but to raise the temperature of the water simply and circulate it in pipes or radiators located in the rooms and spaces to be warmed. There is another and important advantage secured when using this boiler for circulating water instead of steam as a heat medium. This is the increased height of the columns of water acted upon by the heat due to the longer section obtained when starting from the floor and the fact that this pipe conveying the return circulation may enter the boiler also on the floor-level and without rising up and forming a loop in the return-pipe, which is a loss of power and efficiency proportioned to the distance which such return-pipe rises before entering the boiler.

Heretofore in the construction of sectional boilers, whether composed of whole sections spanning the grate and fire-chamber from side to side, or as divided sections covering one-half of the grate, the sections are constructed to be elevated and stand upon a brick or iron foundation, which also forms the ash-pit walls of the completed boiler. In my present invention, however, I dispense with all brick and iron foundations by constructing my boiler-sections to stand directly on the floor, the lower part of such sections below the grate-line forming their own foundation, and thus avoiding the expense of brick or iron ash-pit walls and the labor of elevating the heavy castings onto the foundation—generally half a yard above the floor. This method of constructing cast sectional boilers not only dispenses with said common but useless foundations as to heat effect upon the water in the boiler, but by forming the same from the sections themselves increased heating-surface is obtained in the pipes and tubes extending below the grate and forming the walls of the smoke-flues before described.

In the drawings, A indicates the main integral sections of the boiler, each of which is of cast-iron and hollow, and consists of (see Fig. 5) two substantially parallel vertical tubes 4 4, united by a hollow base 5 at their lower ends, and having extending therebe-

tween at intervals and communicating with the interiors thereof several (three being the preferred number) cross or horizontal ducts 6, 7, and 8. The said vertical tube 3 of the 5 boiler-section A terminates at and communicates with the interior of a horizontal crown-pipe 9 integral therewith and with other tubular parts of said boiler-section, hereinafter referred to, and said vertical tube 3 has a curved 10 upper end, as shown, which terminates at one end of said crown-pipe and, like the tube 3, communicates with the interior thereof. Three tubular branches 10, 12, and 13, constituting elements of said boiler-section A, are 15 arranged one back of the other relative to a central vertical line y^2 through the boiler, as illustrated in Fig. 1, said branches extending from the side of said tube 3 in curved or quarter-turn lines and terminating at the under 20 side of and communicating with the interior of said crown-pipe 9. Said branches are also integral with the said tube 3 and crown-pipe and occupy positions over the grate 14, and are thus directly exposed to the heat of a fire 25 built thereon. Said sections A are so constructed and arranged side by side, as shown in Fig. 2, on the opposite sides of the fire-box within the boiler as to leave open draft-spaces x between the upper parts of the sections, and 30 the latter have cast upon their adjoining sides below said draft-openings x projecting lips v , whose edges are brought into engagement when the sections are in place side by side, thus closing up any opening between the adjoining 35 sections from the lower end of said draft-spaces to a point a little above the grate 14, and there the said closing lip v takes a somewhat different direction, as shown, and terminates under the grate, and from the latter-named 40 point the lip v extends downward to the lower end of the pipe 3, so that when the sections are grouped side by side, as shown in Fig. 2, a close wall will be thereby formed on the opposite sides of the ash-pit. From the upper 45 side of the grate a perforated lip w extends in a like manner from the side of the tube 3, and its upper end terminates at the lower end of that portion of the lip v which terminates near the duct 7. By means of the form given 50 to the lip v between the duct 6 and 7 an air-box y is formed when two sections A are brought together between said sections through which air may flow from the ash-pit B to a point over the fire on the grate, said air 55 passing through the perforations o in said lip w , this latter-named perforated lip, together with the adjoining flat side of the tube 3 next to the grate, serving as a part of the side wall of the fire-box. The said provision for 60 the circulation of air from the ash-pit B through the box y and the perforations o to mingle with the products of combustion in the fire-box affords means for supplying the fire with oxygen, whereby the fuel is consumed 65 under the most advantageous conditions. It will be understood that by means of the above-described construction one of said air-boxes

y is formed between the sides of adjoining sections.

The opposite sides of each of the ducts 6 of the section A are provided with a horizontally-extending lip n , having a curved central notch e two of which form the draft-opening K, (see Fig. 3,) and whose outer edge is in a plane at one end with the edge of said lip v and its opposite end is in a plane with the edge of a vertical lip m , extending from the side of said tube 4 to the same extent that said lip v extends from the side of the tube 3, said lip m , however, extending from the lower 75 end of said tube 4 along its side to the crown-pipe 9, and along the side of the latter to its extremity, as shown in Fig. 5, to the end that when the sections A are brought side to side, as in Figs. 1 and 3, the edges of said lips m , 80 v , and n shall closely abut, thereby compelling the products of combustion from the fire to pass in the direction indicated by the arrow c at the top of the sections, through the openings x , and thence downward past the ducts 85 876, through the draft-opening K, to the main draft-flue h on opposite sides of the ash-pit B. The said main draft or smoke flue h , of which there are two, one on each side of the ash-pit 90 under the grate 14, is formed within that part 95 of the several boiler-sections A surrounded by the lower ends of the tubes 3 and 4 and the ducts 5 and 6, and consequently when the several sections A, which comprise the sides 100 of the boiler, are united together, as shown in Figs. 2 and 3, there is thereby formed said smoke-flue h at the lower ends of and within the above-referred to parts of the sections A, such flue being thereby constructed on each side 105 of the boiler and being continuous from the front to the rear side thereof, as clearly indicated in Fig. 3. In this last-named figure, and also in Fig. 1, the dotted lines z indicate the position of the brick-work, within which when the boiler is set the same is inclosed in the usual manner, and in Fig. 3 the dotted lines i indicate the position of a chimney, and the lines i^2 the direction of flues that in practice 110 extend from the rear ends of the flues h in the lower ends of the sections A to the chimney. It is thus seen that by means of such flue connection with a chimney a direct draft 115 from each flue h is provided, whereby the products of combustion are compelled to move from the fire-box upward among the branch tubes 10, 12, and 13 of the several sections A of the boiler, thence through the passages x 120 between said sections, and thence downward between the walls of a chamber consisting of the vertical tubes 3 and 4 of said sections, past the ducts 6, 7, and 8, and thence through the openings K (see Fig. 3) into said smoke-flue h , and thence to the chimney, as aforesaid. It will be seen also by reference to Figs. 1, 3, and 5 that the side walls of the ash-pit 125 B consist of the united lower ends of the said tubes 3 of the sections A, and therefore the heat existing in the ash-pit acts directly 130 against said walls to impart heat thereto and

to the water contained in those portions of the section-tubes which comprise said walls, and, furthermore, the products of the combustion of the fuel passing from the fire-box act 5 first and most directly against the surfaces of the said branch pipes 10, 12, and 13, which are directly over the grate, and in which the water contained in the boiler is found at its highest temperature, and thence downward, 10 as above described, to the flues *h*, giving off the heat to the surfaces of the boiler-sections as it passes along. By this means it is clearly seen that the heat generated in the fire-box acts continuously and only against the surfaces 15 of the boiler-sections which contain the water to be heated from the time it escapes from the fire-box until it reaches the auxiliary flue above referred to between the boiler and the chimney, and by this means the entire 20 efficiency of the products of combustion is utilized for heating purposes, it being well understood that a boiler connected with a hot-water heating system receives the return-current from the radiators at its lowermost point, 25 and consequently the water in the boiler which surrounds those portions of the boiler-sections which constitute the walls of the smoke-flues *h* is found to be of a lower temperature than that of the products of combustion, 30 which are delivered into said flues from the fire-box, and hence the water surrounding said flues has its temperature raised more or less after reaching said lowest point in the boiler. Furthermore, the radiant heat 35 from the ash-pit against the side walls thereof, as aforesaid, also contributes to the raising of the temperature of the water in the lower flue-containing ends of the said boiler-sections *A*. 40 The above-described advantages pertaining to the construction of the lower draft-flues *h* within the sections of the boiler are wholly lost when such flues are constructed of brick-work, as heretofore practiced, beneath and 45 upon which the lower ends of the boiler-sections rest. The said boiler-sections *A* have their upper ends connected to the opposite sides of a flow-drum *D*—that is to say, the drum toward and into which the water heated in 50 the boiler-sections flows and from which said heated water flows or passes off through an opening *J* in the rear of the drum or a similar opening or openings *J*² in the upper side of said drum. A suitable conducting-pipe is 55 connected thereto leading to the heating-pipes or radiators. Connection between said sections *A* and the drum *D* is made by means of an elbow 15, preferably cast on the crown-pipe 9, and a short connection-pipe 16, connected by one end with said elbow and its 60 opposite end screwed into a socket 18 on the side of said drum, a packing-nut 17 being placed on said pipe 16 and screwing against the face of the socket 18 to lock and pack the joint between said pipe and the drum, any suitable packing being interposed therebetween, if desired. 65

A return-drum *E* is located at the lower end of the boiler and at the lowest point thereof and in axial alignment with the flow-drum *D* and extends under the ash-pit *B* from the front to the rear side of the boiler, as shown in Figs. 3 and 5, and the lower ends of the boiler-sections *A* are connected to said return-drum by means of a pipe 19 for each section, suitably connected by one end thereto and having its opposite end connected to the drum *E* in substantially the same manner as is one end of said pipe 16 connected to the drum *D*, a similar packing-nut 20 being employed, preferably, at the drum-connected end of said pipe 19. The return-pipe from the heating pipes and radiators is connected to the rear end of said drum *E* at the opening *f* (see Fig. 2) or other suitable point thereon. 85 An ash-pit floor of iron covers the drum *E* and connecting-pipes 19. The above-described arrangement of the drums *D* and *E* in axial alignment one above the other and centrally between the sections 90 *A*, together with the long pipe connections 19 between the lower ends of said sections and the drum *E*, permits the vertical expansion of the sections without injury to the joints of the sections and connecting-pipes. 95 A hollow tubular section *C*, constituting a movable bridge-wall, (see Figs. 1 and 4,) is constructed and adapted to be located at the rear side of the fire-box, as shown, and is connected by its upper and lower ends to an 100 intermediate connection-pipe 21 between the drums *D* and *E* at *b* and *b*² thereon by suitable connecting-pipes, which connecting-pipes may be longer or shorter, according to the length of the grate-bars which it is desired to employ, 105 whereby said section *C* may be correspondingly adjusted relative to the rear end of said bars. By this means the water contained in said section *C* becomes heated by its exposure to the fire and flows off at *b* into the pipe 21, 110 and through the latter into the drum *D*, the return-current passing from the drum *E* into the pipe 21 at *b*², and flowing from thence into the lower end of said section *C*, the lower end of which constitutes the rear wall of the ash-pit and its upper end the rear wall of the fire-box. A rib or lip *p* (shown in dotted lines in Fig. 4) is formed on the front side of the 115 said wall *C*, directly opposite the rear ends of the grate-bars, to prevent coal from dropping therebetween. The spaces between the vertical tubes of the bridge-wall are closed by a web to prevent any rear draft therebetween. 120

Having fully described my invention, what I claim, and desire to secure by Letters Patent, is—

1. A metallic boiler-section *A*, consisting of the integral combination of the following members, forming one unit of a sectional boiler, viz: the main vertical pipes 3 4, having horizontal cross-pipes 5, 6, 7, and 8, the said pipes 3 and 4 uniting in a crown-pipe 9, and the curved pipes 10 12 13, whereby is formed the requisite interconnecting internal

water-passages, and, in a group of said sections, the external vertical and horizontal flues to receive and conduct the products of combustion over the entire surface thereof before their exit to a chimney, substantially as set forth.

2. A sectional boiler consisting of a number of hollow metallic sections arranged in two independent groups on opposite sides of the fire-box, each of said groups having therein at the lower end thereof below the fire-grate an independent horizontal smoke-flue communicating with the chimney and receiving the products of combustion through openings in its upper side, the surrounding walls of which flue are composed of grouped portions of said hollow sections, substantially as set forth.

3. A sectional boiler consisting of a number of hollow metallic sections arranged vertically side by side in two independent groups on opposite sides of the fire-box, each of said groups having therein at the lower end thereof below the fire-grate an independent horizontal smoke-flue communicating with a chimney and receiving the products of combustion through openings in its upper side, the surrounding walls of which flue are composed of grouped portions of said hollow sections, substantially as set forth.

4. A sectional boiler consisting of a number of hollow metallic sections arranged in two groups on opposite sides of the fire-box, each

of said groups having therein at the lower end thereof below the fire-grate a horizontal smoke-flue communicating with a chimney and receiving the products of combustion, the surrounding walls of which are composed of grouped portions of said hollow sections, combined with a hollow bridge-wall arranged vertically at the rear of the ash-pit and fire-box, and a flow and a return drum, with which said sections are connected, substantially as set forth.

5. In a sectional boiler, a receiving and a discharge drum, one above the other in axial alignment, to which said sections are connected, combined with a vertical hollow bridge-wall section located at the rear of the grate-bars, having water-circulating connections with said drums, substantially as set forth.

6. In a sectional boiler, a receiving and a discharge drum, one above the other in axial alignment, to which said sections are connected, combined with a vertical hollow bridge-wall section located at the rear of the grate-bars, having variable water-circulating connections with said drums, whereby the bridge-wall section may be set at different distances from the front side of the fire-box, substantially as set forth.

JOHN H. MILLS.
